LAUNDRY WRINGER

Conrad Klein, Philadelphia, Pa.

Application March 15, 1934, Serial No. 715,681

4 Claims. (Cl. 68—32)

This invention relates to laundry wringers, and has for an object to provide a wringer having an improved feeding apron serving also as a protection to the hands of the user.

A further object of the invention is to provide a laundry wringer with the usual and ordinary coacting rollers with an endless apron passing between said rollers and over other rollers, maintaining said apron in a relatively taut condition, 10 and with means for tilting to different angles to accommodate the apron to different positions.

A further object of the invention is to provide, in combination with a laundry wringer having an underlying tray, movable between certain 15 limits to direct the expressed water backwardly into either one or two adjacent tubs; rollers at the opposite ends of the tray over which passes an endless apron passing also between the compression rollers of the laundry wringer, and with 20 means for maintaining said endless apron in a taut condition.

The invention, therefore, comprises in combination with a laundry wringer having the usual and ordinary interacting compression rollers, of a 25 tray underlying said rollers and movable to declinations upon opposite sides of said wringer, the provision of rollers at the opposite ends of said tray over which is extended an endless apron passing between the rollers of the wringer, and with a 30 tension roller beneath the wringer adapted to exert stress upon the apron to maintain the tautness of the apron, irrespective of its expansion or contraction.

The drawing illustrates an embodiment of the 35 invention and the views therein are as follows:

Figure 1 is a view of the improved wringer in side elevation,

Figure 2 is a view of the wringer in end elevation, as indicated by arrow 2 at Figure 1,

Figure 3 is a plan view of the tray and rollers, and

Figure 4 is a detail sectional view of the tensioning roller mounting.

The present invention is adapted to coact with 45 a laundry wringer of widely varying types. In the drawing, a frame 10 is illustrated merely as an example, with rollers 11 journaled therein in the usual manner of wringer rollers. No attempt has been made to show any tensioning 50 means for the rollers 11, it being understood that any usual and ordinary means is within the scope of the invention.

There is also provided beneath the rollers a 55 bar 12 upon which rests a tray 13. Such tray is found already in association with certain types of

wringers and is not per se new in the present case.

The tray is adapted to be moved from the declination shown in full lines at Figure 1 to the declination shown in dotted lines in the same figure, whereby the expressed water flows backwardly 5 into the tub from which the work is being taken.

Mounted upon the ends of this tray 13 are rollers 14. These rollers may be journaled in any approved manner. As shown in the drawing, brackets 15 are secured as by the rivet 16. This, 10 however, is merely an illustrative means of journaling, and any other approved or feasible type is within the scope of the invention.

Rigidly secured beneath the frame 10 are a 15 pair of tubes 17 having slots 18 in their proximate sides. Within each tube 17 a spring 19 is mounted, bearing at its upper end against a disk 20 and at its lower end, against a disk 21. The disk 21 bears upon a trunnion 22 which carries a roller 23. The roller 23 is provided with heads 20 24 at its opposite ends, and the rollers 14 are also preferably provided with heads 25.

While the exact sizes and proportions of the 25 heads 24 and 25 is not essential to the invention, it is considered desirable that the heads 24 shall be large relative to the roller 23, and the heads 25 extend but slightly beyond the circumference of the rollers 14.

An endless apron 26 is provided, passing between the rollers 11 of the wringer, over the 30 rollers 14, over the ends of the tray 13, and under the roller 23. The lineal dimensions of the apron 26 are such that in position it will place the springs 19 under tension, and the springs in association with the roller 23 will, therefore, maintain 35 the apron in taut condition.

This apron is preferably constructed of fabric through which the water expressed by the rollers 11 may flow, but in addition thereto, the fabric is preferably perforated, as at 27, to offer additional escape for the expressed water. 40

The number, relative size and arrangement of perforations 27, relative to the apron 26, is wholly immaterial, and shown in the drawing merely 45 for illustration.

In operation, the tray 13 will be arranged relative to the tubs in the usual well-known manner, and the rotation of the rollers 11 will cause the endless apron 26 to feed continuously between these rollers. 50

The fabrics designed for wringing may be placed upon the longer inclined side of the apron 26, and will pass with such apron between the rollers 11. This provides a considerable degree of safety to the operator, as otherwise, it is nec- 55

essary that the fingers approach closely to the rollers and are likely to be drawn between the rollers to considerable injury to the user.

Also, the apron has a utility in that the fabric 5 may be spread out to a considerable degree and will, therefore, pass between the rollers in a relatively unwrinkled condition. The opposite side of the apron also serves to deliver the fabrics into a receptacle, which may be conveniently 10 placed for the purpose, and much more satisfactory than when delivered only over the tray.

Of course, the laundry wringer herein disclosed 15 may be modified and changed in various ways without departing from the invention herein set forth and hereinafter claimed.

I claim:—

1. The combination with a laundry wringer 20 embodying compression rollers, of a bar beneath the rollers, a tray freely mounted upon the bar, and movable longitudinally and angularly to declined positions upon opposite sides of the rollers, other rollers journaled upon the ends of the tray, an endless apron passing over said last mentioned 25 rollers and between the rollers of the wringer, and means to exert tensioning stress upon the apron, tending to hold the tray upon the bar.

2. The combination with a laundry wringer 30 embodying compression rollers, of a bar beneath the rollers, a tray freely mounted upon the bar and adapted to extend at interchangeable unequal distances upon opposite sides, rollers journaled upon the opposite ends of said tray, an endless apron passing over said last mentioned

rollers and between the rollers of the wringer, and a tension roller engaging said apron beneath the wringer rollers, tending to maintain the tray upon the bar.

3. The combination with a laundry wringer 5 embodying compression rollers, of a bar mounted beneath the rollers, a tray longitudinally movable and tiltable upon the bar and extending upon opposite sides of the rollers, other rollers journaled upon the opposite ends of said tray, an endless apron passing over said last mentioned rollers and between the wringer rollers, a roller mounted beneath the wringer rollers and positioned to exert tensioning stress upon the apron, and springs 10 acting upon said last mentioned roller and providing said tensioning stress tending to hold the tray in attained positions.

4. The combination with a laundry wringer 15 embodying a frame and compression rollers, of a tray mounted beneath the compression rollers 20 and within the limits of the frame and extending upon opposite sides of the compression rollers, rollers journaled upon the opposite ends of said tray, tubes extending downwardly from the frame and provided in their proximate sides with slots, 25 a roller having trunnions extending through said slots and into the tubes, springs mounted within the tubes and exerting tensioning stress upon the trunnions of said last mentioned roller, and an endless apron passing between the compression rollers and about all of the other rollers.

CONRAD KLEIN.
